BRUSH

George K. Davis, Jr., Long Beach, Calif.

Application September 10, 1947, Serial No. 773,285

1 Claim. (Cl. 15—198)

(Granted under Title 35, U. S. Code (1952),
sec. 266)

1

This invention relates to brushes, and more particularly to that feature of brushes having to do with the securing in the brush body of the bristles of tufts of brush material.

It is an object of this invention to provide a brush in which the tufts of brush material may be quickly and easily replaced when they are worn.

It is another object of this invention to provide a brush which may utilize for its bristles short lengths of wire cable, thereby cheapening the manufacture of the brush.

In accordance with these and other objects which will become apparent in the following specification, the brush of the instant invention is constructed of a tubular body having a plurality of slots therein. Tufts of brush material are placed in the slots with the ends of the bristles extending outward of the body and the bights disposed within the body between the two adjacent slots through which the ends project. A ring or cap is secured over the edges of the slots to secure the brush tufts within the body.

Preferred embodiments of the invention will now be described in connection with the accompanying drawings, wherein:

Fig. 1 is an end view of a brush.

Fig. 2 is an exploded perspective view showing details of construction.

Fig. 3 is an end view of a modified form of brush constructed in accordance with this invention; and

Fig. 4 is a side view of the brush body of Fig. 3.

Referring to the drawing, 11 designates a tubular body in the form of a right circular cylinder closed at one end by an end wall 12, preferably formed integral therewith. Projecting into the body 11 and preferably formed integral with the end wall 12, is an axial boss 13, centrally bored at 14 to provide mounting means for a brush rotating shaft (not shown). From the edge 15 of the body 11 which is opposite to the end wall 12, extend a plurality of evenly distributed helical slots 21—28. The width of the slots is sufficient to accommodate tufts of brush material, exemplified by the tuft 31. The brush tuft 31 preferably consists of a short length of stranded resilient material such as wire cable.

The brush is assembled by placing tufts of brush material 31 in adjacent slots 21—28 with the ends 32 of the tuft extending outward of the brush and the bight 33 disposed within the body 11 between adjacent slots. The resiliency of the brush material keeps the bight 33 pressed against the periphery of the boss 13, thereby providing

2

three securing points which determine the shape of the brush tuft. These points are: the adjacent slots through which the brush ends extend, and the periphery of boss 13, against which the bight 33 presses.

It may be preferred to stagger the brush tufts 31 as they are inserted into the slots 21—28. In this event, the first tuft 31 is inserted into slots 21 and 22. The next tuft is inserted into slots 23 and 24. The next tuft is inserted into slots 25 and 26. The next tuft is inserted into slots 27 and 28, thereby completing the first layer of brush material. The next layer begins by inserting a tuft 31 into slots 22 and 23 and is completed by inserting the next three tufts into slots 24—25, 26—27, and 28—21, respectively. In this fashion the tuft layers are built up until they fill the entire length of the slots.

20 A cap 35, having an annular groove 36 on the inner face thereof, is then placed over the edge 15 of the body 11, with the edge residing in the groove 36. The cap 35 is secured to the body 11 by means of screws 37 extending through holes 38 in the cap and into tapped holes 39 in the boss 13. The cap 35 is provided with a center hole 41 registering with the bore 14 to accommodate a rotatable brush mounting shaft.

25 The slots 21—28 are made helical, to produce a more effective brushing action as the brush is rotated.

30 The modified form of brush illustrated in Figs. 3 and 4 has a cylindrical body 51, which is not provided with an axial boss. The securing function of the boss 13 of Figs. 1 and 2 is fulfilled, in this modified form, by the bights 52 of the brush tufts 53. As seen in Fig. 3 the bights 52 of the brush tufts bear against each other in back-to-back relation. An axial mounting bore 54 extends part way into the body 51, stopping short of the slots 55, as seen in Fig. 4.

35 40 To retain the brush tufts 53 in position, and to strengthen the slotted wall of the cylinder 51, a retaining ring 56 is slipped over the edge 57 of the body 51 from which the slots 55 extend. Ring 56 is held in place by means of an annular groove 58, formed in the body 51 adjacent the edge 57.

45 From the foregoing description, it will be seen that there has been described a manner of brush construction which produces, economically and quickly, an improved brush, the bristles of which may be readily replaced when worn.

50 It will be understood that this invention may be made and utilized in many suitable shapes and sizes, and that various modifications and changes 55 may be made in this invention without depart-

ing from the spirit and scope thereof as set forth in the appended claim.

The invention described herein may be manufactured and used by or for the Government of the United States of America for governmental purposes without the payment of any royalties thereon or therefor.

What is claimed is:

A brush comprising a cylindrical body having a plurality of mutually intersecting diametrical slots extending longitudinally inwardly from one end and through a substantial portion of the length thereof whereby said body portion is divided into a plurality of elongated circular sectors each having a cross-sectional area which is substantially less than the cross sectional area of the body at the opposite end thereof, said body being formed of material which has spring characteristics when shaped in the form of said elongated sectors, a plurality of tufts of resilient brush material woven yieldably into said slots, said tufts having the ends thereof extending substantially radially of the body and having the intermediate portions thereof bighted within adjacent slots, the bights of said brush tufts bearing against each other in back-to-back relation within said body, a pre-formed annular groove on the exterior of said body near said first-mentioned end thereof and interrupted by said slots,

10 said groove having a rectangular cross section, and a retaining snap ring releasably seated in said interrupted groove for holding said tufts in said slots, said ring having a rectangular cross section matching that of the groove for free seating of the ring therein, said ring being rigid and having an inner diameter approximately equal to the diameter of the body at the bottom of said groove and less than the exterior diameter of the body between the groove and said end of the body 15 adjacent thereto both before and after the ring is seated in the groove, said segments and tufts being yieldably compressible to permit slipping of the ring onto the exterior surface of the body followed by snap action movement of the ring into the groove.

GEORGE K. DAVIS, JR.
